ATTORNEY.

UNITED STATES PATENT OFFICE.

MAX POLACOFF, OF BROOKLYN, NEW YORK.

BUILDING BLOCK.

Application filed August 16, 1927. Serial No. 213,343.

My invention relates to building blocks and refers more particularly to a block provided with tongues and grooves whereby adjacent blocks may be held in fixed relation to each other.

One object of my invention is to provide a building block that has a tongue on two sides and a shouldered groove on the other two sides.

10 Another object of my invention is to provide a building block that has an air channel on two sides that will register with similar adjacent blocks to provide horizontal and vertical air channels throughout a wall built up therefrom.

15 A still further object of my invention is to provide a building block that has one face formed like brickwork.

I am aware that building blocks with channels, tongues and grooves and holes therein have been used in the art but none of them contemplate the specific formation of this particular block nor do any have a face formed like brickwork.

20 With these and other objects in view, my invention consists of the novel construction and combination of elements hereinafter referred to, specified and claimed and substantially as illustrated in the accompanying drawings, wherein similar numerals refer to like parts throughout the several views, in which:—

Figure 1, is a front elevation of the block.

Figure 2, is an end elevation of the block.

30 Figure 3, is a front elevation of a series of blocks.

The block 1, may be of any suitable shape but is preferably rectangular, has a

shoulder groove 2, with a shoulder 3 and 4, and a groove 5 on the sides 6 and 7 and abutting the bottom of the said grooves are the tongues, 8 on side 9 and 10 on side 11, which tongues fit into the shoulders 3 and 4, of adjacent blocks, thus leaving the air groove 5, free.

45 On the face 12, are grooves 13, formed to imitate brickwork and the back 14, is substantially flat.

Having thus described the preferred embodiment of my invention, I do not wish to limit myself to the exact formation shown, as modifications may be made without departing from the spirit of the invention or scope of the claims.

55 I claim:—

1. A building block comprising a substantially rectangularly shaped body portion having a T shaped groove providing a shoulder on the upper and on one of the end faces, and a square shaped tongue on the lower and opposite end face, adapted to engage with the shoulder of a contiguous block.

60 2. A building block comprising a substantially rectangularly shaped body portion having a T shaped groove on the upper and on one of the end faces providing a square shoulder adapted to engage with the square tongues of contiguous blocks, the tongues on the lower and opposite end faces abutting the shoulders of said grooves providing rectangularly arranged air spaces around each block in a wall built therefrom.

65 Signed at New York, county of New York and State of New York, this 15 day of Aug., 1927.

70 MAX POLACOFF.
